CLAIM

I claim the ornamental design for a bracelet, as shown and described.

DESCRIPTION

FIG. 1 is a perspective frontal side view of the bracelet of my new design, showing the appearance of the bracelet as it would be worn on a person's wrist.

FIG. 2 is a front view of the bracelet of FIG. 1.

FIG. 3 is a left side view of the bracelet of FIG. 1.

FIG. 4 is a back view of the bracelet of FIG. 1.

FIG. 5 is a right side view of bracelet of FIG. 1.

FIG. 6 is a top view of the bracelet of FIG. 1; and,

FIG. 7 is a bottom view of the bracelet of FIG. 1.

The broken lines in FIG. 1 showing a human hand illustrate environmental subject matter only and form no part of the claimed design.
